**COMBINATION MUFFLER AND SPARK ARRESTER
FOR INTERNAL COMBUSTION ENGINES**

Paul S. Moller, 1308 B St., Davis, Calif. 95616

Filed June 30, 1971, Ser. No. 158,663

Term of patent 14 years

Int. Cl. D12—16

U.S. Cl. D14—6 D

FIG. 7.

FIG. 3.

FIG. 5.

FIG. 1.

FIG. 4.

FIG. 2.

FIG. 6.

FIG. 1 is a top plan view of a combination muffler and spark arrestor for internal combustion engines showing my new design;

FIG. 2 is an elevation of one side of the article;
FIG. 3 is an elevation of the other side of the article;
FIG. 4 is an elevation of one end of the article;
FIG. 5 is an elevation of the other end of the article;
FIG. 6 is a bottom plan view of the article; and
FIG. 7 is a perspective view of the article.

I claim:

The ornamental design for a combination muffler and spark arrestor for internal combustion engines, as shown.
